UNITED STATES PATENT OFFICE.

ALFRED SPRINGER, OF CINCINNATI, OHIO, ASSIGNOR TO THE TORSIONAL BALANCE AND SCALE COMPANY, OF OHIO.

BALANCE.

SPECIFICATION forming part of Letters Patent No. 310,545, dated January 6, 1885.

Application filed October 8, 1883. (No model.)

To all whom it may concern:

Be it known that I, ALFRED SPRINGER, a citizen of the United States, residing at Cincinnati, Ohio, have invented new and useful 5 Improvements in Balances, of which the following is a specification.

My invention relates to that class of beam-scales in which the scale-pans are supported above the beam, as in common form of counter- 10 scales for druggists' use. In such balances, especially where, as is the case in scales for delicate weighing, the supporting-standards are thin and light, a weight placed out of the center line of support tends to move the stand- 15 ard out of its true vertical line, and to that extent lengthens or shortens the beam leverage and destroys the true balance. My invention seeks to remedy this evil; and it consists of a pivotally-suspended scale-pan, in combi- 20 nation with the standard, whereby the deflection of the support is practically avoided, all as hereinafter more particularly set forth and claimed.

For the purpose of illustration, I have se- 25 lected and exhibit in the drawings a double-beam "torsion-balance," in which the scale-pans are mounted on supporting-standards above the beams; but it will be obvious that the invention is equally applicable to balances 30 of other kinds.

In the drawings, Figure 1 represents in perspective elevation a portion of a double-beam scale, showing the ends of the beams at one end and the scale-pan support with my in- 35 vention applied; and Fig. 2, a detached view of the upper end of the standard, exhibiting my improved suspended scale-pan support.

Referring, by the aid of the letters of reference herein, to the drawings, A A' designate 40 the upper and lower scale-beams, respectively, mounted on fixed pivots (not shown in the drawings) at their centers, and connected at their ends by wire pivots, acting torsionally, stretched over a skeleton frame, B, the general construction of the balance in this in- 45 stance being such as is described in Letters Patent No. 262,905, granted August 15, 1882, to Frederick A. Roeder. The standard C, in balances of this class, usually carries the scale- 50 pan fixed thereto at the upper end; but it is

manifest that in such construction a weight placed out of the true center of support tends to deflect or bend the standard laterally, and in such case to alter the actual distance thence to the central plane of the fulcrum and to de- 55 stroy thereby the true balance of the beams. As a remedy for this difficulty, I bifurcate the standard, as shown, and between its upper extremities, c c, suspend a scale-pan support, D, by means of suspending links or hangers d d. 60

The construction exhibited in the drawings is simple and effective, in which the pan-support D is a wire ring secured to the suspending-links d, which project upward at the sides and turn outward to form pivotal sup- 65 ports resting in open slots in the upper ends of the arms c c. The scale-pan E itself may be substituted for the ring, and thus suspended; but in general it is preferable to construct the parts separately, as shown. When thus 70 arranged, a weight, w, being placed in the pan at one side of the plane of vertical motion, the parts so adjust themselves as to retain the center of gravity in such plane.

It will be obvious that the details of con- 75 struction in the pivotal bearings of the sus- pended scale-pan may be varied in many ways without departing from the essential principle of my invention, which is also equally appli- 80 cable to simple beam-scales.

I claim and desire to secure by Letters Patent—

1. In a beam-scale of the character described, in combination with the beam, a scale-pan pivotally hung from a point of support above the 85 beam, substantially as and for the purpose set forth.

2. In a beam-scale, a bifurcated standard for carrying the scale-pan above the beam, in combination with a scale-pan pivotally sus- 90 pended between its bifurcated arms, substan- tially as and for the purpose set forth.

In testimony whereof I have hereunto set my hand in the presence of two subscribing witnesses.

ALFRED SPRINGER.
